(57) **CLAIM**

The ornamental design for a sensor assembly, as shown and described.

DESCRIPTION

FIG. 1 is a top, front, left perspective view of a first embodiment of the claimed design for a sensor assembly; FIG. 2 is a front view thereof; FIG. 3 is a back view thereof; FIG. 4 is a right side view thereof; FIG. 5 is a left side view thereof; FIG. 6 is a top view thereof; FIG. 7 is a bottom view thereof; FIG. 8 is a top, rear, right perspective view thereof; FIG. 9 is a top, front, left perspective view of a second embodiment of the claimed design for a sensor assembly; FIG. 10 is a front view thereof; FIG. 11 is a back view thereof; FIG. 12 is a right side view thereof; FIG. 13 is a left side view thereof; FIG. 14 is a top view thereof; FIG. 15 is a bottom view thereof; FIG. 16 is a top, rear, right perspective view thereof; FIG. 17 is a top, front, left perspective view of a third embodiment of the claimed design for a sensor assembly; FIG. 18 is a front view thereof; FIG. 19 is a back view thereof; FIG. 20 is a right side view thereof; FIG. 21 is a left side view thereof; FIG. 22 is a top view thereof; FIG. 23 is a bottom view thereof; and, FIG. 24 is a top, rear, right perspective view thereof.

(Continued)

The broken lines showing the remainder of the sensor assembly depict environmental structure and form no part of the claimed design.

1 Claim, 24 Drawing Sheets
